UNITED STATES PATENT OFFICE.

GAETANO FERIANI, OF ROME, ITALY, ASSIGNOR TO SOCIETA BREVETTI FERIANI, OF ROME, ITALY.

WINCH.

1,393,436.

Specification of Letters Patent.

Patented Oct. 11, 1921.

Application filed March 8, 1920. Serial No. 363,976.

To all whom it may concern:

Be it known that I, GAETANO FERIANI, a subject of the King of Italy, and resident of Rome, Italy, have invented certain new and useful Improvements in Winches, of which the following is a specification.

The present invention relates to improvements in winches, and more particularly to new means for the automatic distribution 10 of the rope in regular windings about the winding drums of a winch.

The invention is characterized by the fact 15 that the rope or cable which winds up upon the winch drum, locates itself in the form of a spiral the size of the cable making no difference to the regular distribution of it, the means for guiding and automatically distributing the cable upon the drum surface or upon the layers of cable already 20 wound, being controlled by the threads formed by the cable when it is taken up during the rotation of the winch.

This function is obtained by means of a suitable member which comes into contact 25 with the windings of the cable as the same is taken up upon the drum, the said member producing the movement of a distributing member which serves to arrange the cable into regular windings from one end to the 30 other of the winch drum.

For a better understanding of the invention the same is described with reference to the accompanying drawings which show by 35 way of example, a preferred form of construction of the invention.

In the drawings:

Figure 1 is a side elevation of the device.

Fig. 2 is a diagrammatic plan view of the device.

Fig. 3 is a detail of the controlling device for connecting the distributing member to the controlling means.

Fig. 4 is an enlarged perspective view of the cable guide.

Fig. 5 is a view of the beginning of the cable winding and the formation of the first layer of the cable on the drum.

Fig. 6 is a view showing the beginning of the second layer of cable on the drum.

Figs. 7 and 8 show positions assumed by the wedge during the winding of cable on the drum.

With reference to the figures in particular, in which the same reference characters 55 indicate the identical parts, 1 is the wind-

ing drum, 2 the side flanges, and 3 the drum shaft. On the winch frame is mounted the device for controlling the distribution of the cable. This device comprises an arm 7, the end whereof bears a wedge 9 intended to contact with the windings of the cable upon the drum. The arm 7 is pivoted at 10 so as to swing in a vertical plane, the pivoting point 10 being free to rotate in a horizontal plane. To that purpose the pivot 10 is made in one piece with a sleeve 11 threaded about the vertical shaft 12, secured in any suitable way to the winch frame. On the shaft 12 is also mounted to freely swing, a second arm 13 which reproduces the movements of the arm 7, but only those movements that this latter arm performs in the horizontal plane. The connection between the arm 7 and the arm 13 is clearly shown in Fig. 1, said connection 15 being formed by cut away portions of the sleeves 11 and 44, as will hereinafter be fully explained.

The free end of the arm 13 is bent upward and is pivotally connected to the underside of the plate 14. This plate is supported by two horizontal guides 15, between which the plate 14 is free to reciprocate, the movement thereof taking place in a direction parallel to the shaft of the drum 1. 20 The plate 14 is provided with a slot 16 (Figs. 2 and 4) the direction of which is transverse to the direction of the movement of the plate 14. A pivot 17 engages the slot 16, the pivot being securely fixed to a plate 25 18 sliding into the guides 19. The position of these guides is at right angles to the guides 15, whereby the plate 18 moves at right angles to the plate 14. The plate 18 forms a part of a prolonged arm 20 the 30 end of which is connected to the free end of a lever 21 pivoted at 22, upon the winch frame.

The lever 21 is connected with a triangular frame 23, which is also pivoted about 35 the vertical axis 22. The free end of the frame, which end is also the vertex of the triangle, is provided with bearings supporting a grooved pulley 5. This pulley bears the cable 4, as shown, and distributes it 40 upon the drum. The cable 4 passes also between two pulleys or rollers 24 located at each side of the pivoting shaft 22, and from said pulleys the cable runs to a second pulley 6, thence to the body that the winch must 45

rise or retain (in the case the winch is intended to be used for aeronautical purposes). The operation of the device is clearly understood by looking at fig. 2. In fact any displacement of the arm 7 is reproduced by the arm 13 which in turn produces the reciprocation of the plate 14. This reciprocation of the plate 14 through the pivot 17 of the plate 18 engaging the slot 16, produces a reciprocating movement at right-angles of the plate 18. This latter through the arm 20 swings the lever 21 about the axis of pivot 22 and causes an angular movement of the frame 23, to which the lever 21 is secured.

Inasmuch as the cable 4 passes over the pulley 5 at the free end of the frame 23, the cable 4 will of course in its running toward the drum 1 as it is taken up, be gradually and continuously moved from one end to the other of the drum, and as this latter rotates, the cable locates itself in the regular form of a screw thread.

The winding operations will be understood by reference to Figs. 5, 6, 7 and 8. Fig. 5 is a view illustrating the beginning of the winding on the drum and the formation of the first layer of cable. Fig. 6 shows the completion of the first layer of cable on the drum and the starting of a second layer. Fig. 7 shows the position assumed by the wedge 9 when the first layer of cable is completed and the wedge contacts with the end flange of the drum. Fig. 8 shows the position assumed by the wedge 9 in grinding the distributor when starting the formation of a new layer.

This operation is in fact controlled from the movement of the arm 7, which contacts with its wedge 9 with the threads of the cable as the same is winding up on the drum 1. The wedge 9 contacting with the threads of the cable causes the continuous displacement of the lever 7 from one end to the other of the drum, until one layer of cable has occupied the entire length of the drum (Fig. 7), and thereafter the wedge, and its arm, begin to move in the reverse direction (Fig. 8) to return to the starting point, and so on again until the winch stops. The arm 7 may also oscillate in a vertical plane to accommodate the increasing diameter of the drum 1, due to the several layers of cable taken up during the winding operation, and vice versa.

The several parts stated, have their size, and their movement combined in such a way to produce a reciprocating movement of the frame 23 and of course of the pulley 5 from one end to the other of the drum, and with that speed necessary to dispose the cable in the desired way, said speed being a function of the diameter of the cable 4.

Besides, the threads of the cable, assume the function of screw threads, between

which is threaded the wedge 9 connecting to the arm 7.

The thrust pulley 6 is journaled on the supporting member 25 which is itself pivoted about a horizontal axis upon the winch frame thus being free to swing for following the variable inclination of the cable 4 when the winch is used for aeronautical purposes. To that end the support 25 is provided with an arm 26 to the upper end whereof are mounted two grooved pulleys 27 between which the cable runs. Furthermore the arm 26 is pivoted with its lower extremity about the shaft of the pulley 6, which disposition permits the arm 26 to swing in a plane at right angles with the plane passing through the axis of the support 25. The combination of these two movements allows the pulley 27 to follow the cable in any direction, which is of peculiar advantage in the case of winches to be used for aeronautical purposes.

In Fig. 2 the two extreme positions of the parts, are indicated respectively in full lines and in dotted lines.

From what has hereinbefore been said, and from the drawings it is evident that when the cable is given out from the drum 1 the device has no function, and to prevent the movement of the several parts, the applicant has devised suitable means to stop the movement of said parts. This may be obtained by taking the wedge 9 out of contact with the cable upon the drum 1. To that effect the lever 28 is used, pivoted at 29 to the winch frame, (Fig. 1) the extended lower portion 30 of said lever bearing upon the rear extension 31 of the arm 7.

A coiled spring 32 keeps in engagement the extension 30 with the extension 31 and in the mean time forces the arm 7 and its wedge 9 against the drum 1, to assure the necessary contact between the wedge 9 and the cable threads. With the operation of the lever 28, that is by pulling it towards the right in Fig. 1, the rear extension 31 of the arm 7, is forced down, and the wedge 9 is raised leaving the drum. Therefore, as soon the wedge 9 contacts no more with the cable, the device becomes inoperative. But this would leave the parts affected by the action of cable 4 passing on the pulley 5 during the unwinding operation. To avoid such difficulty the connecting point between the lever 21 and the frame 23 is provided with a coupling device which may be brought into or out of positive engagement by the action of a flexible controlling cable 33, acted on by the handle 34 mounted upon the lever 28, as shown.

The frame 23 will remain free to swing about its pivot 22 and will follow the movement of the cable from right to left, and vice versa, when the cable is given out from the drum 1.

The coupling is shown in section in Fig. 3.

Referring to this figure, at the pivotal point 22, and into the lower side of the frame 23 is formed a coupling device comprising two members, one of which is integral and moves with the lever 21, and the other with the frame 23. The coupling member of the frame 23, has two teeth 35 between which may be brought into engagement the transversal locking bar 36. This bar is free to move vertically and is cross mounted into a sleeve 37, to which the lever 21 is secured. A coiled spring 38 located under the bar 36, and contained within the sleeve 37, continually forces the locking bar into engagement with the teeth 35 of that part of the coupling secured to the frame 23.

The lower portion of the pivot 22 is hollow, and is provided with two elongated slots 39 through which passes a stud 40 bearing upon the bar 36. To the stud 40 is secured, as shown, the wire of the controlling device 33. By pulling on the wire the stud 40 is pulled down, taking with itself the bar 36 against the tension of the spring 38. The lowering of the bar 36, leaves out of engagement the teeth 35, thus separating the two members of the coupling. Therefore the frame 23 is free to swing about its pivot 22. When the end of the frame to which is mounted the pulley 5, is in the right position, with relation to the arm 7, this latter is lowered into contact with the drum; in the mean time the handle 34 is released, thus releasing the pull on the wire. The spring 38 will push the bar 36 again into engagement with the teeth 35 and the frame 23 is again coupled with the lever 21, and through the parts described, to the arm 7.

For allowing a certain play, between the arm 7 and the arm 13, for accommodating the variations of position between the frame working conditions, the sleeve 11 to which 23 and the arm 7 arising from the actual working conditions, the sleeve 11 to which is pivoted the arm 7, and the sleeve 44 to which is secured the arm 13 are loosely interconnected, leaving a space between the offset portions or teeth 41 of the sleeves 11 and 44 respectively. The amount of play between the two sleeves is regulated by means of the screws 42 screw-threaded through the portion 41, and coming at a suitable distance with the teeth 43, which distance may be regulated at will, as it is easily understood.

Having now particularly described and ascertained the nature of my invention and in that manner the same is to be performed what I claim is:

1. In a winch, means for the automatic distribution in regular windings of the cable upon the winch drum, said means being characterized by the combination of an arm provided with a wedge contacting with the cable threads upon the drum, with a swing-

ing frame for distributing the cable in regular windings, the movement of this frame being synchronized with the movements of the arm, said movements being transmitted from one member to the other by means of suitable positive driving connections. 70

2. In a winch, means for the automatic distribution of a cable in regular windings upon the winch drum, said means comprising in combination: a wedge contacting with the cable threads upon the drum, an arm supporting said wedge, a sleeve to which the arm is pivoted, a vertical shaft for supporting the sleeve, a second sleeve interconnected with the first sleeve, a second arm secured to the second sleeve and following the movements of the first named arms, a sliding member moving in a horizontal plane, and to which the second arm is pivotally connected, a second sliding member moving at right angles with the first member, and means to connect the first sliding members to the second sliding member and for transmitting the movement from one to the other. 75 80 85

3. In a winch, means for the automatic distribution of the cable in regular windings about the winch drum, which means comprises a sliding member reciprocating in a horizontal plane and parallel to the axis of the drum, a diagonal slot formed into said sliding member, a second sliding member moving in a horizontal plane at right angles with the first member, a boss extending downward from the second sliding member and engaging the slot of the first sliding member, the two sliding members reciprocating with synchronous movements, and guides for supporting said members, substantially as described. 90 95 100

4. In a winch, means for the automatic distribution of the cable in regular windings about the winch drum, said means comprising a swinging frame pivoted about a vertical axis, a pulley mounted to the free end of said frame and upon which the cable passes, the alternate swinging movement of the frame disposing the cable in regular windings from one end to the other of the drum said frame being connected, through the reciprocating sliding members, to the arm bearing upon the cable, the movement of said swinging frame being in synchronism with the movement of the arm, essentially as described. 105 110 115

5. In combination with means for the automatic distribution of cable in regular windings about a winch drum, a swinging frame pivotally connected to operative connecting means, said connecting means being characterized by a coupling mounted into the pivoted joint of the swinging frame, said coupling being formed by two members, one integral with the frame, and the other to the lever controlling the movement of said frame, a cross bar engaging the coupling 120 125 130

member of the frame and moving with the lever, a coiled spring bearing on the cross bar to bear the same into engagement with the swinging frame, and controlling means for engaging or disengaging the cross bar, as essentially described.

In testimony whereof I have hereunto

signed my name in the presence of two witnesses.

GAETANO FERIANI.
